DESIGN FOR A LIGHT FIXTURE

William Lescaze, New York, N. Y., assignor to
Pass & Seymour, Inc., Syracuse, N. Y., a cor-
poration of New York

Application November 22, 1944, Serial No. 116,481

Term of patent 14 years

(CL. D48—4)

To all whom it may concern:

Be it known that I, William Lescaze, a citizen of the United States of America, residing at New York, New York, have invented a new, original, and ornamental Design for Light Fixture, of which the following is a specification, reference being had to the accompanying drawing, forming part thereof.

In said drawing:

Figure 1 is a front or face view of a light fixture showing my design;

Figure 2 is a side elevation of the fixture, and Figure 3 is a top or plan view of the same.

The dominant features of my design reside in the portions shown in full lines.

I claim:

The ornamental design for a light fixture, as shown and described.

WILLIAM LESCAZE.
